mesne assignments, to Reconstruction Finance
Corporation, Chicago, Ill., a corporation

Application October 9, 1937, Serial No. 168,285

2 Claims. (Cl. 15—147)

This invention relates to a mop and more particularly to a mop in which the mop head is readily withdrawable from the mop body, the mop being useful for dusting and other purposes.

5 An object of the invention is to provide a mop of extremely simple construction which is readily flexible in practically all directions and in which the mop head can be compressed laterally to permit its insertion within or removal from the 10 mop body. A further object is to provide a mop head which can be readily manipulated by a novice and which can be assembled or disassembled without changing the shape of the spring loop carried by the head. A further object is to 15 provide a mop head equipped with a spring loop portion which is maintained in a desired elongated shape and which can be operated in loosely held as well as tightly held position within the clamp of the head. Other specific objects and 20 advantages will appear as the specification proceeds.

The invention is illustrated in a preferred embodiment, by the accompanying drawings in which—

25 Figure 1 is a plan view of a mop embodying my invention, the yarn of the mop body being omitted; Fig. 2, a broken plan view of a mop similar to that shown in Fig. 1, the tie strings being loosened; Fig. 3, a plan view of the clamp-30 ing member shown in flat position just before being bent to engage the spring loop; Fig. 4, a detail sectional view, the section being taken as indicated at line 4 of Fig. 1; Fig. 5 a plan view of the mop provided with the usual yarn or 35 thread; and Fig. 6, a transverse sectional view, the section being taken as indicated at line 6 of Fig. 5.

In the illustration given, A designates a handle provided with a metal threaded ferrule A'; B, 40 a wire coil serving as a union; C, the mop head; and D, the mop body.

The handle A may be of any suitable type or construction. It is equipped, as shown, with the usual metal ferrule A' which is threaded to 45 receive the coil union B. The coil union B is of well known construction and need not be described in detail.

The mop head C may be of any suitable construction. In the form illustrated, I provide a 50 metal clamp 10 which is formed, as illustrated more clearly in Figs. 2 and 3, from a single piece, bent upon itself at 11. The clamp is provided with aligned holes 12 through which extends a 55 bolt 13 engaged by a nut 14. The outer aligned

ends of the clamp 10 provide a curved passage 15 adapted to receive a spring coil 16.

The spring coil 16 is preferably formed as illustrated more clearly in Figs. 1 and 2. The coil is provided on one side with a reduced portion 17 which enters and locks with the adjacent larger end of the spring. It is found that this connection provides a secure and permanent union of the two ends so that there is no tendency for them to separate under stress or flexure. At the 10 same time I find that the reduced portion 17 because of its resistance to bending helps in maintaining the spring in the elongated shape shown in Fig. 2. This construction also facilitates the lateral bending of the entire spring when the 15 same is to be inserted within the pocket of the mop body D.

I prefer to locate the portion 17 along one side of the spring loop, as illustrated in Fig. 2, while at the same time bringing an integral and 20 uniform portion of the spring within the clamping chamber 15 of clamp 10. I have found that when a continuous portion of the spring is clamped within the member 10 that more even and uniform flexing of the entire spring results. 25 Also, should the clamp work loose, the nut 14 being worked to some extent off of the bolt 13, there is no tendency for the spring to slip out of the clamp, as there would be if free ends of the spring were enclosed within the clamp. When 30 the clamp becomes quite loose, it is only necessary for the operator to tighten the nut and the spring is again securely held in position.

The mop body D may be of any suitable construction. In the illustration given, I have provided a fabric pocket formed by sewing two overlapping pieces of fabric together, the pieces being stitched together as indicated by the dotted line 18. The yarn strings or threads 19 are stitched to the fabric body along its edges and other 40 suitable points so as to provide a substantially continuous covering of yarn. It will be understood, however, that the forming of the yarn body may be varied considerably to adapt the 45 mop to any particular desired use.

It will be observed that the stitch as illustrated provides a substantially fan-shaped pocket 20, the pocket being of constricted cross-section at its lower end. The fabric is perforated near its lower end at 21 to permit a tie member 22 to be 50 drawn therethrough.

In assembling the mop, the tie member is allowed to remain loose and the spring 16 of the head is compressed laterally so as to narrow its dimensions sufficiently to permit it to enter the 55

constricted portion of the pocket. The spring is then fed forward, the succeeding portions of the spring 16 being successively compressed so as to permit it to pass into the pocket. Once within 5 the pocket, the spring 16 expands to fill the pocket as illustrated more clearly in Figs. 1 and 2. The threaded end of the clamping member 10 is screwed within the coil union B, and the coil union B is threaded upon the ferrule A' of handle 10. After the mop head has been placed in position, the tie member 22 is drawn tightly around the coil union B and tied as illustrated in Fig. 1. In disassembling, it is merely sufficient to untie the member 22 and then draw the head rearwardly, the pressure exerted by the sides of the fabric pockets being sufficient to laterally compress the spring 16 and to permit it to slide 15 out of the constricted opening of the pocket. The operation of insertion and removal of the 20 head is extremely simple, requiring no removal or release of the spring member 16. Should the spring become loose at any time, there is no tendency for it to fly apart; it remains in the clamp 10 until the operator can tighten the nut. The 25 spring head is extremely flexible, bending uniformly under strain.

While in the foregoing description, I have set forth a specific form of the device as illustrative, it will be understood that there may be many 30 changes in the details of construction without

departing from the spirit of my invention. The foregoing detailed description has been given for clearness of understanding only, and no unnecessary limitations should be understood therefrom, but the appended claims should be construed as broadly as permissible, in view of the 5 prior art.

I claim:

1. In a mop head of the character set forth, a clamping member adapted for attachment to a 10 handle, and a coil spring body in the form of a loop having an intermediate portion secured within said clamping member, said coil spring body having telescoping ends providing a secure union between the ends and a relatively stiff portion 15 on one side of said spring body, the inside diameter of the larger end being substantially the same as the outside diameter of the smaller end.

2. In a mop head of the character set forth, a clamping member adapted for attachment to a 20 handle and a coil spring body in the form of a loop having an intermediate portion secured within said clamping member, said coil spring body having telescoping ends outside of said clamping member and providing a relatively stiff 25 portion and also secure union between the ends, the inside diameter of the larger end being substantially the same as the outside diameter of the smaller end.

WARREN G. BAILEY. 30
